F. W. THURSTON.

VAPORIZER.

APPLICATION FILED OCT. 13, 1915.

1,282,654.

Patented Oct. 22, 1918.

UNITED STATES PATENT OFFICE.

FRED WALLACE THURSTON, OF SPOKANE, WASHINGTON, ASSIGNOR, BY MESNE ASSIGNMENTS, TO THURSTON MOTOR FUEL GASIFIER COMPANY OF CALIFORNIA, A CORPORATION OF CALIFORNIA.

VAPORIZER.

1,282,654.

Specification of Letters Patent.

Patented Oct. 22, 1918.

Application filed October 13, 1915. Serial No. 55,661.

To all whom it may concern:

Be it known that I, FRED W. THURSTON, a citizen of the United States, residing at Spokane, in the county of Spokane and State of Washington, have invented certain new and useful Improvements in Vaporizers, of which the following is a specification.

This invention has for its object an improved means for vaporizing a supplied explosive mixture for explosive engines.

An object of the invention is to provide the screen with a bottom deflector for deflecting the major portion of the incoming fuel directly against the primary heating surface, for subsequent passage through the heated screen, said bottom having a direct passage opening for a small volume of the fuel to reduce the tendency to form a vacuum just above said deflecting body.

A further object is to provide a retainer for retaining the fuel in contact against the primary heating surface for a portion of its travel, said retainer being in such spaced relation with respect to the screen heater as to expose all of the area of the screen heater for passage therethrough of the fuel. In this connection, it is a feature of this invention to reduce the vacuum forming tendency to such an extent that there will be only sufficient draw to induce a portion of the fuel to pass through the screen behind the retainer.

Claims to the apparatus, whereby the condensate is collected and held for enrichment of the next in-coming mixture, have been transferred to my co-pending application filed December 4, 1916, Serial No. 134,965.

Other features and objects of my improved means for vaporizing and re-starting without priming will be more fully described in connection with the accompanying drawing and will be more particularly

pointed out in and by the appended claims. The accompanying drawing shows in vertical section, one embodiment of my invention.

As illustrated, 1 designates, as a whole, an intake manifold for a four cylinder explosive engine and it will be observed that the manifold is constructed to drain into an attaching terminal end 2 to which the device of my invention is secured.

My improved vaporizer includes an outer shell 3 having inlet and outlet pipes 4 and 5 for passage through the outer shell of a heating medium such for instance as the exhaust gases from the engine. The outer shell 3 has an inner shell 6, preferably cylindrical, which functions as a primary heating surface and between which inner shell and outer shell the exhaust gases pass. I conveniently reduce the inner shell 6, as indicated at 7, and thread on to the reduced end 7 a cap 8 to which the terminal 2 may be secured by its flange 9, in any desired manner. The reduced end 7 forms an outlet 10 which is preferably equal in diameter to the terminal 2. The bottom of the shell 3 is recessed at 11 to receive a deflector 12 which preferably extends transversely across the path of the supplied mixture. The outer margin of the deflector 12 is interposed between shell 3 and a fitting 13 the latter being coupled at 14 to a pipe 15 leading from a suitable means of supply of the fuel mixture, such as the carburetor. The deflector 12 is provided with a series of openings 16 which are preferably laterally disposed, radially, with respect to the bore 17 so that the incoming fuel will be deflected outwardly, radially, against the inner face 18 of shell 6. For this purpose, the fitting 13 is flared at 19 to provide passage for a suitable volume of the mixture.

I mount upon the deflector 12 an obconic screen 20 having its lower margin 21 spaced a considerable distance from the shell 6 and its upper margin 22 disposed closely adjacent shell 6. The top of the screen 20 is open, as indicated at 23, the opening 23 being preferably equal in diameter to the outlet bore 10. Thus it will be seen that the screen 20 is interposed in the path of the mixture in such a manner that all of the mixture leaving shell 6 is suction drawn by the engine through said screen.

After an explosive engine has been brought to a position of rest subsequent to operation, the vapor in the intake or manifold condenses after the parts cool and this leaves the walls of the intake coated with a sweat or covering of globules of liquid fuel. This liquid condensate very efficiently and quickly impregnates air or a thin mixture to form a rich explosive vapor. Now this condensate drains down the intake and because of

the fact that the screen collector is interposed in its path and because the mesh openings of this collector are too small for the liquid fuel to pass therethrough, I have 5 found that after my engine has cooled off, and in taking out the screen 20 that the latter was coated and dampened with liquid fuel.

Now in re-starting an engine, especially 10 when using a low grade hydro-carbon, but even in the case of gasoline, the first inrush or influx of air fails to pick up a sufficient amount of the liquid fuel so as to enter the cylinder as a rich vapor and therefore in 15 most cases it is necessary to prime in one form or another. However, with my improved device the first influx of re-starting thin mixture is so rich by passage through the film coated collector that it is not necessary 20 to prime the engine because the first influx mixture is sufficiently rich to make an effective explosion. The cylinder exhausts from the starting explosions, resulting from this condensate enriched air, will immediately 25 heat the primary surface 18, and the screen 20, so that the richer influx immediately following the condensate enriched mixture, will quickly be vaporized to sustain continuous explosions in the engine. The 30 importance of providing means for heating the screen collector, in addition to having a collector for performing this function will now be clear.

I have pointed out that the deflector 12 35 deflects the fuel against the primary heating surface 18 but I will now describe an improved retainer for positively holding substantially the complete annular volume of fuel against the primary heating surface for 40 a portion of the travel of the fuel.

I have shown my improved retainer at 24 as being a flaring truncated cone having its 45 smaller end mounted at 25, on the deflector 12, in spaced relation from the screen 20 and 50 overhanging the openings 16, the upper end 26 extending toward but not into contact with the primary heating surface 18. Thus 55 the function of the retainer 24 is to engage the previously deflected fuel and retain such fuel in engagement with the surface 18. A most important feature is to dispose the retainer in spaced relation from the screen so that the full area of screen surface will be presented for passage therethrough of 60 the fuel.

If that portion of the deflector 12 disposed inwardly with respect to passage openings 16 were wholly imperforate, then there would be such a strong tendency to form a 65 vacuum just above deflector 12 as would constitute additional and unnecessary restriction of flow to the engine. I do not wish to entirely eliminate this vacuum forming tendency but I find it advantageous to so 70 reduce this tendency that flow will not be

impeded or restricted and yet all of the screen area will be presented to the fuel. Thus, I provide a direct passage 27, preferably screened as at 28 so that a relatively small volume of fuel may pass axially upwardly through the vaporizer without impinging against primary heating surface 18 and without going through screen 20. However, this direct passage opening 27 admits such a small volume as to amount to about 75 one-fortieth of the total volume. Now the function of this direct passage opening is to reduce the vacuum creating tendency above the deflector 12 but such vacuum will be formed sufficiently to draw down over the 80 top 26, of the retainer 24 a portion of the volume for passage between that part of the screen located behind the retainer thereby making all of the screen surface available as a breaker and at the same time getting full 85 advantage of the retainer in holding the major portion of the mass against the primary heating surface.

In order to provide an all-screen interior for the secondary breaking screen shell, I 90 dispose a screen 29 between the screen 28 and the screen 20 so that none of the condensate draining into the collector will fall upon or engage an imperforate surface. The advantage of this is that this condensate 95 is taken up more freely by the incoming air when it is presented to the incoming air on a screen surface.

It is believed that the advantages of my improved means may be clearly appreciated 100 from the foregoing description, and while I have shown and described one specific form of my invention, I do not wish to be limited thereto except for such limitations as the claims may import.

I claim:—

1. In a device for vaporizing fuel, an outer primary heating shell, means for applying heat to said shell, an inner screen shell, means for deflecting the fuel against said heating shell before it is drawn through said screen shell, a retainer extending along and in spaced relation with respect to said screen shell for retaining the deflected fuel in contact with the primary shell, substantially as described.

2. In a device for vaporizing fuel, an outer primary heating shell, means directly supplying heat to said shell, an inner screen shell, extending along said primary shell to 120 substantially the full length of the latter, means for deflecting the fuel outwardly from said inner screen shell against the interior of said primary heating shell for subsequent passage of the fuel through and into 125 said inner shell, and a retainer coacting with said means and projecting longitudinally along said primary heating shell to retain the deflected fuel thereagainst, said retainer being in such spaced relation from 130

said inner screen shell that all of the area of the latter will be presented for passage of the fuel therethrough, substantially as described.

- 5 3. In a device for vaporizing fuel, an outer primary heating shell, an inner screen shell extending along and abreast of said primary shell, a deflector forming the bottom of said screen shell and arranged to deflect the fuel against said primary shell prior to its passage into and through said screen shell, said deflector having an opening for direct passage of such a small volume of fuel directly into said screen shell
- 10 15 as to reduce the vacuum forming tendency immediately above said deflector, substantially as described.
4. In a device for vaporizing fuel, an outer primary heating shell, an inner screen shell disposed in such close relation along

the length of said primary shell as to be heated thereby to a high temperature, a deflector for deflecting the fuel against said primary shell prior to passage of the fuel through said screen shell, a retainer extending along and in spaced relation with respect to said screen shell for retaining the deflected fuel against said primary shell, and said deflector having an opening therein for direct passage of sufficient volume of fuel into said screen shell to reduce the vacuum forming tendency immediately above said deflector only sufficient to cause such vacuum to draw a portion of the fuel over said retainer and through that portion of the screen shell behind the retainer, substantially as described.

In testimony that I claim the foregoing as my own I hereby affix my signature.

FRED WALLACE THURSTON.
